UNITED STATES PATENT OFFICE.

JAMES R. RICKETTS, OF LONG BEACH, CALIFORNIA.

PRIMING MEANS FOR INTERNAL-COMBUSTION ENGINES.

1,221,378.

Specification of Letters Patent. Patented Apr. 3, 1917.

Application filed June 6, 1916. Serial No. 102,101.

To all whom it may concern:

Be it known that I, JAMES R. RICKETTS, a citizen of the United States, residing at Long Beach, in the county of Los Angeles and State of California, have invented a new and useful Improvement in Priming Means for Internal-Combustion Engines, of which the following is a specification.

In the operation of internal combustion engines and particularly the type of such engines employed for supplying motive power to motor vehicles of the modern types, with both high and low grade fuels, when the engine has become cold, it is a difficult 10 thing at times to start the engine running, especially after a relatively long period of rest, it being necessary to spin the crank shaft, if no starter medium is provided, until a sufficient amount of the fuel has been 15 introduced into the combustion chambers of the engine. Even when a self starter is employed, as in all modern cars, quite a protracted effort is necessary on the part of the starter before the engine may be placed in 20 operation.

My invention, therefore, relates to means for obviating the difficulties suggested above and has for an object the provision of means applicable readily and easily to the intake 25 manifold of the engine whereby a limited supply of fuel from an auxiliary tank may be introduced into the manifold and from thence into the combustion chambers of the engine by means of the initial suction in the 30 engine cylinders caused by but a slight movement of the pistons when the crank shaft is turned preparatory to starting the engine, the fuel tank provided with my device being capable of holding but a small 35 quantity of fuel and being located at a point preferably beneath the level of the fuel intake of the engine so that the fuel fed from the tank may only be supplied by 40 suction and not otherwise.

A further object of my invention is to 45 provide means for operably connecting the auxiliary fuel supply means with the starting rod or lever which operates the self starting mechanism, so that the supply of 50 fuel from the auxiliary tank may be introduced in a small jet into the engine simultaneously with the movement of the starter, thus reducing the effort of the starter to a minimum and effecting a considerable economy in the operation of the vehicle.

A further object is to provide means for

adapting my device to vehicles of both the manually and mechanically started types, and in the latter type of vehicles, for operating my device by either manual or mechanical means.

A further object is to provide means in the priming valve for admitting a limited quantity of air from the atmosphere for introduction with the fuel into the intake 60 manifold, so that the priming operation may be greatly facilitated. Other objects may appear as the description of my invention progresses.

Referring to the drawings, in which similar characters of reference indicate the same parts throughout the several views, Figure 1 is a sectional elevation of a modern automobile showing the application of my priming device thereto, and with certain parts of the 70 vehicle and operating mechanism omitted for clarity. Fig. 2 is a fragmentary plan of Fig. 1. Fig. 3 is a transverse elevation, substantially enlarged, of the lever which connects the starting mechanism with the priming device for simultaneous operation. Fig. 75

4 is an enlarged longitudinal section of the priming valve; Fig. 5 is a transverse section of Fig. 4 on the line 5—5; and Fig. 6 is a 80 similar section of the same on the line 6—6.

One of the modern types of motor vehicles 85 is shown in the drawings for the purpose of illustrating my invention, but it should be understood that my device may be as readily applied to any of the several types of such 90 vehicles as to the particular type shown, it being necessary to change only the manner of connecting the priming and starting means from that shown, and this change should only be slight, as will readily appear. 95 In the drawings 1 is a motor vehicle body having a radiator 2 at the front end of the hood as usual, 3 is the engine which is provided with the intake manifold 4 connected with a carburetor, not shown, by means of 100 the pipe 5. The main fuel supply tank 6 is shown in front of the dash board 7 above the level of the engine and the fuel is supplied therefrom by means of a pipe 8.

I provide the auxiliary fuel supply tank 9 105 which is located just behind the radiator 2 and above the frame member 10. The tank 9 has a suitable filling plug or cap 11 provided with a suitable air vent to permit the entrance of air to the tank when the fuel is 110 withdrawn at the top and a discharge pipe 12 connects the tank with the valve body 13,

2. the pipe 12 being of very small flexible tubing with a suitable union 14 interposed therein for facilitating its connection with the tank and valve body and the upper end thereof being connected to the bottom of the valve body midway of the ends.

The discharging end of the valve body 13 is bored at 15 to receive the end of the small pipe 16 which has a union 17 and is connected to the intake manifold 4, the pipe being secured suitably to the end of the valve body so as to prevent leakage of the fuel therefrom. The valve body 13 has a large valve chamber 18 formed in the end opposite the discharge pipe 16 and the outer end of the chamber 18 is threaded internally to receive the similarly threaded extension 19 on the valve head 20. The inner end of the valve chamber 18 has a tapered valve seat 21 formed therein to receive the valve 22 the stem 24 of which is slidably mounted in a bore 23 in the valve head and carries a spring 25 within the chamber 18 which is adapted to compress between the end of the valve head and the valve. The valve seat 21 communicates with the discharge opening 15 so as to permit the flow of the fuel from the pipe 12, through the chamber 18, and thence into the pipe 16 by means of which it is conducted to the intake manifold 4. The spring 25 serves to normally close the valve and is compressed when the valve stem is moved outwardly in the valve head 20, thus opening the communicating passage between the pipes 12 and 15. The valve head is enlarged at the outer end so that it may be tightly forced against the end of the valve body for preventing leakage of the fuel at this point. A very small air vent 27 is provided in the top of the valve body 13 by means of which a supply of air may be admitted to the chamber 18 for mixture with the liquid fuel. The vent 27 also serves to prevent any slight leakage of the fuel through the valve to the manifold when the valve is closed but is imperfectly seated, as it is possible that such a leakage may ensue should the vent be omitted.

The valve stem 24 is connected at the outer end with one end of an operating rod 28 which may be extended through the dash board 7 and provided with a suitable knob 29, as shown in full lines in Figs. 1 and 2, or this rod may be extended through the radiator 2 as shown in broken lines, the position of the valve body 13 being changed, as shown, to conform to the change in the valve operating rod. When the device is used on cars not provided with self starters, the rod 28 should preferably be positioned as shown in broken lines so that the end of the rod may be grasped by the hand when the starting crank is turned by manual effort, but in the case of cars having self starters this rod should be convenient to the

driver of the vehicle, or, extended through the dash board 7.

As shown in full lines, the rod 28 has a collar 30 in front of the dash board and the starting rod 31 which is slidably or pivotally mounted in the foot board 32 and is operable by the foot of the operator, has a similar collar 33, both of the collars 30 and 33 being held immovably on the rods by means of set screws 34. A lever 35 is pivoted near the center on a pin or screw 36 extending through the lugs 37 of the bracket 38 which is suitably attached to the dash board 7, and the opposite ends of this lever are provided with yokes 39 and 40 which respectively engage the rods 28 and 31 and the collars 30 and 33 thereon. Thus, when the starting rod 31 is depressed for starting the vehicle, the lower yoke 40 of the lever is moved forward by means of its engagement with the collar 33 on the rod 31, and the upper yoke 39 of the lever similarly moves the rod 28 rearward by means of its engagement with the collar 30 on the rod 28. This movement of the valve operating rod 28 withdraws the valve 22 from its seat 21 in the valve body 13 and the initial movement of the crank shaft of the engine by the starting mechanism serves to suck a quantity of the liquid from the tank 9 into the manifold 4 by way of the pipes 12 and 15, the extremely small caliber of the pipes 12 and 15 always insuring a sufficient supply of the fuel with but a very slight movement of the pistons which create the suction.

In engines of this character an excessive supply of fuel into the combustion chambers will effect the stoppage or "killing" of the engine and if it were possible for the fuel from the tank 9 to leak into the manifold during the operation of the engine this result might ensue. It is to be observed, however, that such a leakage is impossible with the device shown, for the tank 9 being positioned below the level of the intake of the engine, the fuel from the tank can only be introduced into the manifold 4 by means of the suction therein and this suction serves to close the valve passages and to more firmly seat the valve 22.

It is conceived to be possible to substantially modify the structure of my invention and change it from that shown in order to meet conditions which are peculiar to various types and makes of vehicles, without enlarging the scope or departing from the spirit of my invention.

Having thus described my invention, what I claim is:

1. In a priming device for internal combustion engines, the combination with the engine and the fuel intake manifold therefor, and starting means for said engine, of a fuel tank arranged to permit the withdrawal of the fuel therefrom by suction and

supported below said manifold, a combined air and fuel valve intermediate of and connected with said tank and said manifold, and an operating member for said valve extended to a point convenient to the operator and capable of operation independently of and with said starting means for simultaneously admitting air and fuel to the engine cylinders coincidently with the initial movement of the pistons.

2. In a priming device for internal combustion engines, the combination with the engine and the fuel intake manifold therefor, of a liquid fuel tank arranged to permit the withdrawal of the fuel therefrom by suction, said tank being supported at a point lower than the plane of said manifold, a combined air and fuel valve intermediate of and connected with said tank and said manifold for normally closing com-

munication therebetween and for admitting desired quantities of air and fuel into the engine elements, the starting rod for cranking said engine, a rod connected with said valve and extended into the body of the vehicle for manually operating said valve, and a pivotally supported lever connected with said operating rod and with said starting rod for opening said valve coincidently with the operation of said starting rod for admitting fuel and air to the engine cylinders with the initial stroke of the pistons.

Signed at Long Beach, in the county of Los Angeles and State of California, this 31st day of May, 1916.

JAMES R. RICKETTS.
